JOHN A. RENNIE, OF LYNDHURST, NEW JERSEY, ASSIGNOR TO UNDERWOOD TYPE-WRITER COMPANY, OF NEW YORK, N. Y., A CORPORATION OF DELAWARE.

TYPE-WRITING MACHINE.

1,090,878.

Specification of Letters Patent. Patented Mar. 24, 1914.

Application filed December 21, 1910. Serial No. 598,581.

To all whom it may concern:

Be it known that I, JOHN A. RENNIE, a citizen of the United States, residing in Lyndhurst, in the county of Bergen and State of New Jersey, have invented certain new and useful Improvements in Type-Writing Machines, of which the following is a specification.

This invention relates to platen-shifting or displacing mechanisms for typewriting machines to facilitate the insertion and adjustment of pads or sheaves of sheets around the platen.

It constitutes an improvement on the device disclosed in the application of Alfred F. F. Kurowski, filed Oct. 27, 1910, Serial No. 589,455.

One object of the present invention is to enable the platen displacement operation to be easily and quickly accomplished without necessitating care in the adjustment of the platen; to which end an abutment, controlled by the usual pressure roll release mechanism, is shifted into the path of a stop turning normally with the platen, whereby the operator need only shift or displace the platen until it is arrested by the abutment. Said abutment also prevents rotation of the platen during the displacement thereof.

Another object is to simplify and improve mechanisms of this class to render them inexpensive to manufacture and readily applicable to existing machines.

The platen is hinged to supports at points eccentric to its axis, and is loosely mounted relatively to its axle, to permit displacement of the platen relatively to the axis. The platen is normally locked to its axle. A lever may be operated to release the locking latch and subsequently swing the platen upwardly on its hinge or fulcrum.

Other objects and advantages will herein-after appear.

In the accompanying drawings, Figure 1 is a perspective, showing the invention applied to the right hand end of the platen frame of an Underwood writing machine, parts being broken away and parts omitted. Fig. 2 is an end view, showing the platen locking and displacing mechanism in normal position. Fig. 3 is a front view partly in section of the mechanism applied to the platen. Fig. 4 is an end view, showing the platen lifted or displaced. Fig. 5 is a detail

section on line X—X of Fig. 6, showing the manner of hinging the platen to the axle. Fig. 6 is a platen head.

A platen axle 1 extends through a platen 2 and is journaled in the ends 3 of a platen frame, said ends being connected by a paper shelf 4 and a tie rod 5. Rear and front pressure rolls 7 and 8 coöperate with the platen to feed the sheets around beneath the platen and up in front thereof.

The platen is hinged at its opposite ends eccentrically of its axis on pivots 9; mounted in arms or supports 10, the latter fast to the axle 1. This construction permits the platen to swing upwardly to facilitate the insertion of work sheets. Heads 11 secured to the platen ends are slotted at 12 (Fig. 6) concentric with the hinge or fulcrum points 9; said slots extend downwardly from the axis of the platen and the axle 1 of the platen passes through them. Normally the platen is centered relatively to the axle (Fig. 2) and locked thereto by latches 13 mounted on a shaft 14 extending longitudinally of the platen and journaled in the heads 11. Teeth 15 on said latches enter notches 16 formed in keepers 17 fast to the axle, and preferably formed integral with the hinge arms 10. This locking action takes place at points remote from the axle 1, thereby affording stability to the platen, since any shake is not multiplied. A spring 18 holds the latches engaged with the keepers.

To displace the platen, the operator first depresses a finger piece 19, journaled in one of the platen frame ends 3, which operates through the usual crank 20, link 21 and cam shaft 22 to cast off the pressure rolls 7 and 8 against the tension of springs 23. The depression of the finger piece 19 rocks an elbow lever 24, 25 supported on the tie rod 5, one arm 24 of which is connected to the crank 20, whereby to shift an abutment 26 into the path of a stop 27 preferably carried by one of the fulcrum arms 10, to arrest the rotation of the platen.

The platen is lifted by means of a lever 28 pivoted at 29 to one end of the platen frame. When swung forwardly, said lever rocks an arm 30 (which may be integral therewith) 105 to draw rearwardly a dog 31 pivoted at 32 to the arm and having a hooked end 33. Said dog first engages one of the latches 13 by a lug 34 on said latch over the front of which the hooked end 33 catches to release 110

the latch from its keeper 17. This rocks the shaft 14 to release the latch at the opposite end of the platen.

The releasing throw of the latches is limited by a stop 35, struck by one of said latches prior to the completion of the stroke of the lifting lever 28, further movement of which continues to press the hooked end 33 of the dog against the lug to swing the platen upwardly on its hinges or fulcrums 9 which are located out of the line of draft of the dog against stop 35. The heads 11 move relatively to the axle 1. The face of the lug 34 engaged by the dog is inclined to prevent the latter from slipping off as the platen is lifted.

The lever 28 is arrested by a stop 36 thereon which may strike one of the platen frame ends 3 at which time, the pivotal connection 32 between the dog 31 and arm 30 has described an arc about the pivotal point 29 of the lever (see Figs. 2 and 3) until it lies on the opposite side thereof, having passed the straight line position whereby to lock the platen in elevated position. The pad of sheets is then inserted in the machine, after which the lever 28 is returned to normal position (Fig. 2) to release the platen and the latch. A spring 38 holds the dog normally idle and may assist in maintaining the lever 28 in locked position when the lever is shifted. The platen may now swing back by gravity to a position concentric with the axle, the teeth 15 of the latches riding on guide faces 37 of the keepers 17 until they reach the notches 16 into which they are snapped by returning spring 18. The finger piece 19 is then returned to place to restore the pressure rolls 7 and 8 and remove the abutment 26 from the path of stop 27, leaving the platen free to turn.

Variations may be resorted to within the scope of the invention, and portions of the improvements may be used without others.

Having thus described my invention, I claim:

1. In a typewriting machine, the combination with a platen frame, and a platen axle journaled therein, of a platen, a pivot supported in said frame therefor eccentric of the ends of the platen, a movable latch normally connecting the platen to its axle, and means to move the latch from normal position to release the platen, and means to swing the platen on said pivotal support.

2. In a typewriting machine, the combination with a platen frame, and a platen axle journaled therein, of a platen, arms fast on the axle and pivotally connected to the platen eccentrically thereof, a latch to lock the platen to the axle to turn therewith, and means to release the latch and swing the platen on its pivotal connection with the arms relatively to the frame.

3. In a typewriting machine, the combi-

nation with a platen frame and a platen axle journaled therein, of a platen pivotally supported eccentrically of its ends, means to lock the platen to the axle so as to turn therewith, means to arrest the rotation of the platen, and means to swing the platen on its pivotal supports relatively to the frame and axle, subsequently to its release from the latter.

4. In a typewriting machine, the combination with a platen frame and platen axle journaled therein, of a platen connected to the axle to swing relatively thereto, means to lock the platen against swinging, pressure rolls, means to cast off and return said rolls, an abutment shiftable by the release of the rolls, into the path of a stop normally turning with the platen to arrest the platen, and means to release the platen from its axle and to swing the platen relatively to the frame.

5. In a typewriting machine, the combination with a platen frame and a platen axle journaled therein, of a platen pivotally connected to the axle to swing eccentrically thereof, locking means to fasten the platen concentric to the axle, a stop normally turning with the platen, an abutment shiftable into the path of the stop to arrest the platen, and means to release the platen from its axle and to swing the platen relatively to the frame.

6. In a typewriting machine, the combination with a platen frame and a platen axle journaled therein, of fulcruming arms on the axle, a platen hinged on the arms and having slots concentric with its hinge and leading from the axis, said axle entered in said slots, means to lock the platen to the axle concentrically therewith to turn with the axle, means to arrest the platen, and means to release the platen from its axle and swing it eccentrically thereof and relatively to the frame.

7. In a typewriting machine, the combination with a platen frame and a platen axle journaled therein, of a platen normally concentric with the axle, and pivotally connected therewith at points eccentric to the axle, a latch on the platen, a keeper on the axle engaged by the latch to lock the platen concentrically with the axle, means to arrest the rotation of the platen, and means to release the latch and displace the platen eccentrically of the axle and relatively to the frame.

8. In a typewriting machine, the combination with a platen frame and a platen axle journaled therein, of a platen normally concentric with the axle, and pivotally connected therewith at points eccentric to the axle, means to lock the platen concentrically with the axle to turn therewith, a stop normally turning with the platen, pressure rolls for the platen, casting off and restoring

mechanism therefor, including a finger-piece, an abutment shifted by said finger-piece into the path of said stop when the rolls are cast off, and means to release the lock and displace the platen eccentrically of the axle and relatively to the frame.

9. In a typewriting machine, the combination with a platen frame and a platen axle journaled therein, of a platen normally concentric with the axle, and pivotally connected therewith at points eccentric to the axle, means to lock the platen concentrically with the axle to turn therewith, a stop normally turning with the platen, pressure rolls for the platen, casting off and restoring mechanism therefor, including a finger-piece, an elbow lever having a normally idle abutment operated by said finger-piece to shift the abutment into the path of the stop when the rolls are cast off, and means to release the lock and displace the platen eccentrically of the axle and relatively to the frame.

10. In a typewriting machine, the combination with a platen frame and a platen axle journaled therein, of a platen normally concentric with the axle, and pivotally connected therewith at points eccentric to the axle, means to lock the platen concentrically with the axle to turn therewith, a stop normally turning with the platen, an elbow lever having a normally idle abutment to be entered in the path of the stop, and means to release the lock and displace the platen eccentrically of the axle and relatively to the frame.

11. In a typewriting machine, the combination with a platen frame and a platen axle journaled therein, of a platen through which said axle passes, fulcruming arms on the axle pivotally supporting the platen eccentrically thereof, means to lock the platen to the axle to turn therewith, a stop connected to the axle, an abutment shiftable into the path of the stop to arrest the rotatable platen, and means to release the platen from its axle and displace said platen eccentrically of said axle and relatively to the frame.

12. In a typewriting machine, the combination with a platen frame and a platen axle journaled therein, of a platen normally concentric with the axle, and pivotally connected therewith at points eccentric to the axle, means to lock the platen concentrically with the axle to turn therewith, a stop normally turning with the platen, an abutment shiftable into the path of the stop to arrest the rotatable platen, and means to release the platen from its axle and displace said platen eccentrically of said axle and relatively to the frame.

13. In a typewriting machine, the combination with a platen frame and a platen axle journaled therein, of a platen through

which said axle passes, fulcruming arms on the axle pivotally supporting the platen eccentrically thereof, means to lock the platen to the axle to turn therewith, a stop connected to one of said fulcruming arms, an abutment shiftable into the path of the stop to arrest the rotatable platen, and means to release the platen from its axle and displace said platen eccentrically of said axle and relatively to the frame.

14. In a typewriting machine, the combination with a platen frame and a platen axle journaled therein, of a platen normally concentric with the axle and pivotally connected therewith at points eccentric to the axle, a latch secured eccentrically of the platen end and shiftable in a plane parallel therewith, and a keeper on the axle to lock the platen concentrically thereof, means to arrest the platen and prevent its rotation, and means to release said platen from its axle and swing it eccentrically thereof and relatively to the frame.

15. In a typewriting machine, the combination with a platen frame and a platen axle journaled therein, of a platen normally concentric with the axle and pivotally connected therewith at points eccentric to the axle, a latch secured eccentrically of the platen end and shiftable in a plane parallel therewith, and a keeper on the axle to lock the platen concentrically thereof, and having a guiding face for said latch when released, means to arrest the platen and prevent its rotation, and means to release said platen from its axle and swing it eccentrically thereof and relatively to the frame.

16. In a typewriting machine, the combination with a platen frame and a platen axle journaled therein, of a platen normally concentric with the axle, and pivotally connected therewith at points eccentric to the axle, means comprising a latch to lock the platen to the axle to turn therewith, means to arrest the platen at a predetermined point and prevent its rotation, and means engaging the latch to release the platen from its axle and swing it on its pivotal supports relatively to the frame.

17. In a typewriting machine, the combination with a platen frame and a platen axle journaled therein, of a platen through which said axle passes, fulcruming arms on said axle pivotally connected to the platen eccentrically thereof, said arms having notches, latches on the platen to enter the notches and lock the platen fast to the axle, a stop on one of said arms normally turning with the platen, an abutment shiftable into the path of the stop, to arrest the platen and prevent rotation thereof, and means to release the platen from its axle and swing it on its pivotal supports relatively to the frame.

18. In a typewriting machine, the com-

5 bination with a platen frame and a platen axle journaled therein, of a platen normally concentric with the axle, and pivotally connected therewith at points eccentric to the axle, means to lock the platen to the axle to turn therewith, means to arrest the platen, and lifting mechanism to engage that portion of the locking means on the platen, to release the platen from the axle and to swing it on its pivotal supports relatively to the frame.

10 19. In a typewriting machine, the combination with a platen frame and a platen axle journaled therein, of a platen normally concentric with the axle, and pivotally connected therewith at points eccentric to the axle, a latch on the platen, a keeper on the axle engaged by the latch to lock the platen and axle together, and lifting mechanism to release the latch and swing the platen on its pivotal supports relatively to the frame, and lock it in displaced position.

15 20. In a typewriting machine, the combination with a platen frame and a platen axle mounted therein, of a platen pivotally supported eccentrically of its axis and loose on the axle, means to lock the platen to its axle concentrically therewith to turn with the axle, means to arrest the platen, a lever on the frame, and a dog operated by the lever to release the platen from its axle and swing said platen on its pivotal supports relatively to the frame.

25 21. In a typewriting machine, the combination with a platen frame and a platen axle mounted therein, of a platen pivotally supported eccentrically of its axis and loose on the axle, means to lock the platen to its axle concentrically therewith to turn with the axle, means to arrest the platen, a lever on the frame, and a dog operated by the lever to release the platen from its axle and swing said platen on its pivotal supports relatively to the frame, said dog and lever being so constructed and their pivots being so arranged that the platen is retained in displaced position at the end of the platen releasing stroke.

30 22. In a typewriting machine, the combination with a platen frame and an axle mounted therein, of a platen loosely mounted relatively to the axle and hinged eccentrically of its axis, means to lock the platen to the axle to turn therewith, means to arrest the platen, a lever pivoted to the frame, a dog hinged to the lever to release the platen from its axle and swing it on its hinge, said hinge connection between the dog and lever passing from one side to the other of the pivotal support of the lever to lock the platen in displaced position.

35 23. In a typewriting machine, the combination with a platen frame and an axle mounted therein, of a platen loosely mounted relatively to the axle and hinged eccentrically of its axis, means to lock the platen to the axle to turn therewith, means to arrest the platen, a lever pivoted to the frame, a dog hinged to the lever to release the platen from its axle and swing it on its hinge, said hinge connection between the dog and lever passing from one side to the other of the pivotal support of the lever to lock the platen in displaced position.

40 24. In a typewriting machine, the combination with a platen frame and an axle mounted therein, of a platen loosely mounted relatively to the axle and hinged eccentrically of its axis, a pivoted latch to lock the platen to the axle to turn therewith, means to arrest the platen, a lever pivoted to the frame, and a dog engaging the pivoted latch to release the platen from the axle.

45 25. In a typewriting machine, the combination with a platen frame and an axle mounted therein, of a platen loosely mounted relatively to the axle and hinged eccentrically of its axis, a latch to lock the platen to the axle to turn therewith, a dog engaging the latch to release the platen from its axle, said dog hooking onto the latch, a stop engaged by the latch when released to arrest the latch and enable the dog by pressure thereagainst to swing the platen on its hinges relatively to the frame, and a lever controlling the dog.

50 26. In a typewriting machine, the combination with a platen frame and an axle mounted therein, of a platen loosely mounted relatively to the axle and hinged eccentrically of its axis, means to lock the platen to the axle, a stop at the hinge to turn with the platen, an abutment shiftable into the path of the stop, and means to release the platen from the axle and to swing said platen on its hinges relatively to the frame.

55 27. In a typewriting machine, the combination with a platen frame and a platen axle mounted therein, of a platen pivotally supported eccentrically of its ends, keepers fast on the axle, latches mounted at opposite ends of the platen to engage the keepers and lock the platen concentric with the axle, a shaft connecting the latches, and means to release the latches and swing the platen on its pivot relatively to the frame and axle.

60 28. In a typewriting machine, the combination with a platen frame and a platen axle mounted therein, of a platen pivotally supported eccentrically of its ends, means to lock the platen to the axle at points remote from the latter and adjacent the periphery of said platen, and means to release the locking means and swing the platen on its pivot relatively to the frame and axle.

65 29. In a typewriting machine, the combi-

nation with a platen frame and a platen axle mounted therein, of a platen loosely mounted relatively to the axle and hinged eccentrically of its axis, a finger-piece which when depressed swings an abutment into the path 5 of a stop normally turning with the platen to arrest the latter, and a lever controlling a dog which hooks into a latch, normally locking the platen concentric to the axle to 10 turn therewith to release said latch, which then engages a stop, whereupon further pressure on the lever causes the platen to swing upwardly on its hinges, it being held in lifted position owing to the passage of 15 the line of pull of the dog past the lever fulcrum, the return of said platen to normal position being secured subsequently to the release of the dog from the latch by a follower operated from said finger-piece which 20 also removes the abutment from the path of the stop.

30. In a typewriting machine, the combination with a platen frame and a platen axle mounted therein, of a rotatable platen 25 adapted to be shifted transversely of its axle, a stop on the platen for arresting said platen in position to be shifted, a second stop on the platen, and an arm on the frame to seize said second stop to turn the platen 30 around said first stop as a fulcrum to shift the platen transversely.

31. In a typewriting machine, the combination with a platen frame and a platen axle mounted therein, of a rotatable platen 35 adapted to be shifted transversely of its axle, a stop on the platen for arresting said platen in position to be shifted, pressure rolls, means to release said rolls, a stop set by said roll releasing means to coöperate 40 with said platen stop, a second stop on the platen, and an arm on the frame to seize said second stop to shift the platen on said first platen stop as a fulcrum.

32. In a typewriting machine, the combination 45 of a platen cylinder, a platen shaft, means for shifting the platen transversely of the shaft when the platen is in a pre-determined angular position, a stop on the platen, and pivoted means movable into the 50 path of rotation of said stop, whereby the platen upon being rotated, may be arrested in the angular position in which the shifting means is operative.

33. In a typewriting machine, the combination 55 of a platen shiftable away from its normal bearings when turned to a certain angular position, a paper pressure roll, means for throwing the latter to and from the platen, and means controlled by said 60 roll throwing means for arresting the platen in the proper angular position for shifting the same.

34. In a typewriting machine, the combination 65 with a platen and a shaft relatively to which it is shiftable, of a pressure roll

for said platen, means for moving said roll from the platen, a stop on the platen, and an abutment for arresting said platen by its stop set by the means moving said pressure roll away from the platen.

35. In a typewriting machine, the combination 70 with a platen and an axle therefor, of hinges eccentric to the axis of said platen, a stop on said platen, a pressure roll for said platen, a key for moving said pressure roll away from said platen, an abutment set by 75 said key for arresting said platen by its stop, and a handle for shifting said platen on said hinge when it is arrested by said stop.

36. In a typewriting machine, the combination 80 with a platen and a shaft therefor, of a hinge adjacent the periphery of the platen connecting said shaft to said platen, a stop adjacent said hinge, a pressure roll for said platen, a key for casting off said pressure roll, an abutment moved by said key into the path of said stop to arrest the platen, a latch holding said platen in its normal position with relation to said shaft, 90 a lug on said latch, and a dog arranged to catch on said lug, to first release said latch, and then shift said platen on said stop as a center.

37. In a typewriting machine, the combination 95 with a platen and a shaft therefor, of a plate at one end of said shaft, a pivot eccentric to the platen by which said plate is attached to the platen, a stop forming an extension of said plate, a pressure roll for 100 said platen, a key for casting off said pressure roll, and an abutment moved by said key into the path of said stop to arrest the platen.

38. In a typewriting machine, the combination 105 with a platen and a shaft therefor, of a plate at one end of said shaft, a pivot eccentric to the platen by which said plate is attached to the platen, a stop forming an extension of said plate, a pressure roll for 110 said platen, a key for casting off said pressure roll, an abutment moved by said key into the path of said stop to arrest the platen, a latch pivoted on the platen normally holding the platen in position on the shaft, a lug on said latch, and a dog arranged to catch said lug to release said latch and then shift said platen around said stop.

39. In a typewriting machine, the combination 115 with a platen frame and a platen axle mounted therein, of a platen pivotally supported eccentrically of its axis and loose on the axle, means to lock the platen concentrically with its axle to turn therewith, means to arrest the platen, a lever, and a dog 120 connected thereto to release the platen from its axle and swing the platen on its pivotal supports relatively to the frame, said dog so connected with the lever that its line of pull passes from one side of the lever ful- 125

crum to the other during the movement of the lever.

40. In a typewriting machine, the combination with a rotatable platen and a shaft for said platen, of hinges eccentric to the axis of said platen connecting it to said shaft, means for shifting said platen on said hinges, a paper pressure roll for said platen, a key for moving said pressure roll away from the platen, a stop on the platen, and an abutment set by said key when the pressure roll is moved from the platen for arresting said platen by said stop in the proper position for shifting the platen.
41. In a typewriting machine, the combination with a platen and a shaft therefor, of hinges connecting said platen to said shaft eccentrically to the axis of said platen, a pressure roll for said platen, a key for moving said pressure roll from said platen, a stop on said platen, an abutment set by said key when said pressure roll is moved away from the platen to arrest said platen

by its stop, a latch normally holding said platen so that its shaft is concentric with it, a lever, a dog operated by the lever for moving said platen on its hinges relatively to its shaft, and a lug on the platen adapted to be engaged by said dog for first releasing said latch and then shifting the platen.

42. In a typewriting machine, the combination with a platen and a shaft therefor, of a plate pivoted eccentrically of said platen on the platen, a latch for holding the platen concentric with the shaft, a lug on said latch, a pressure roll for said platen, a key for moving said pressure roll away from said platen, an abutment set by said key to catch on said plate, and a manually operated dog for catching said lug for releasing said latch and then shifting the platen relatively to its shaft.
